PRESSURE CARBURETOR

Stanley M. Udale and Bert Beard, Detroit, Mich.,
assignors to George M. Holley and Earl Holley

Application November 1, 1943, Serial No. 508,573

1 Claim. (Cl. 261—69)

The object of this invention is to devise the simplest possible carburetor of the pressure type which will give correct metering for changes in load, altitude and temperature.

In the drawing, 10 is the air entrance. 11 is the small venturi which creates the necessary pressure difference between the entrance and the throat in response to airflow so that this double venturi acts as an air meter. 12 is the pipe connecting the throat of the small venturi 11 with a chamber 13, the right-hand side of which is formed by a flexible diaphragm 14 supported by a spring 15 which is adjusted by an adjusting screw 16. The diaphragm 14 carries a tapered needle 17 which controls the flow of fuel from the passage 18. The flow of fuel in the passage 18 is supplied by an engine driven pump 19. The chamber 18¹ communicates with the passage 18 through an elongated restricted passage 36 and the right-hand wall of this chamber 18¹ is formed by a diaphragm 34. This diaphragm is supported by a spring 20 which controls a valve admitting fuel to the passage 21 and thus controls the pressure drop past the needle 17. This diaphragm 34, when it is moved to the left by the spring 20, admits fuel into the pipe 21 by moving the valve 25 to the left and the fuel discharges past the spring-loaded valve 22 into the inlet passage of the engine or into the center of the supercharger (not shown).

Changes in altitude and temperature are corrected by a barometric element 25 located in a chamber 26, which chamber is connected by a large passage 27 with the air entrance 10 at the downstream end of the venturi and on the engine side of the throttle 23. A relatively small pipe 28 connects chamber 26 with the throat of the venturi. A tapered valve 29 allows air to flow from chamber 26 to the chamber 13. It will be noted that there is a restriction 37 in the pipe 28. The pipe 12 is connected to the throat of the venturi 11 through the opening 38. A stop screw 30 prevents the valve 17 from seating entirely. This prevents damage to the valve or to the valve seat and also permits a minimum quantity of fuel to flow so that the engine can idle. A throttle stop 31 prevents a throttle lever 32 from entirely closing the throttle 23. A pressure release valve 33 prevents the pressure in the chamber 13 from becoming excessively high so that the pressure in passage 18 does not vary more than 3 or 4 lbs. per square inch.

In order to equalize the variation of air pressure in the air entrance, a pipe 34 connects the air entrance with a chamber 35 located to the

right-hand side of the diaphragm 14. This pipe 34 takes its air from the air entrance leading to the venturi 10. As a rule, air is blown into a scoop from the propeller; alternatively, a supercharger provides the air entrance with air under pressure.

Operation

Assume that the engine is in a plane flying at low altitudes, say below 7,000 feet. The valve 29 is closed and the full depression in the venturi acts on the diaphragm 14. The valve 17 opens and fuel flows under a pressure which may vary from 10 to 14 lbs. per square inch. The construction of the diaphragm 34 and the spring 20 limits the pressure drop at the needle 17 to the stiffness of the spring 20 which is a constant. Hence, the fact that the pump 19 and the relief valve 33 will not control the pressure anywhere near constant does not matter. At altitude, that is, say above 7,000 feet, the barometric element 25 begins to expand and admits air from chamber 26 into the chamber 13 reducing the fuel flow so as to keep the mixture ratio constant. At extreme altitudes the venturi 10 will choke the engine unless a supercharger be connected so as to force air into the venturi 10 if the venturi is between the throttle and the engine. In the event that there is such a choking, the depression in passage 27 may cause the element 25 to expand still more and the mixture will not become excessively rich as it otherwise would. On the other hand, if the compressed air is supplied to the air entrance 10, then the pressure of this air will be the same in the air entrance as in chamber 35, the air entrance pressure being transmitted through the pipe 34.

The pipe 28 causes a flow down the unrestricted passage 27 and up the passage 28. The restriction 37 in the pipe 28 causes the pressure in the chamber 26 to equal the pressure downstream below the venturi 10. At air flows higher than normal, there is a tendency for the mixture ratio to become rich because the air expands and the liquid gasoline does not. When the air expands due to high velocity and also expands due to high altitude, in both events the capsule 25 expands the valve 29 travel to the right. The travel of the valve 29 to the right bleeds air into 13 at a higher pressure than the pressure in the throat of the smaller venturi 17 transmitted through the opening 38. Hence, the valve 29 corrects for altitude and also for load and for temperature. By the circulation of air through chamber 26, the element 25 is held at the temperature in 10.

What we claim is:

A carburetor having an air entrance, a double venturi therein comprising a small venturi discharging into the throat of a larger venturi, an air chamber having a passage communicating with the downstream side of said larger venturi, a source of fuel under constant pressure, a second air chamber, a moving wall therefor, a fuel control valve connected to said moving wall, a passage connecting said first air chamber to the 10

second air chamber, a valve in said passage, a barometric element in said first chamber connected to said valve whereby said valve is opened by a drop in pressure in the downstream portion of said larger venturi due to high air flow and also to an increase in altitude and in temperature, a passage connecting said second air chamber to the throat of said smaller venturi.
